UNITED STATES PATENT OFFICE

GEORGE O. BISHOP, OF SALT LAKE CITY, UTAH

FAN

Application filed September 26, 1927. Serial No. 222,165.

This invention relates to fans, and is designed primarily for moving large volumes of air at low pressure, especially, being adapted to heating and ventilating work, more especially for warm air furnace work, and the invention has for its object to provide, in a manner as hereinafter set forth, a fan so constructed and arranged whereby pressure is built up and the air propelled in practically a straight line parallel to the shaft, driving the rotor.

A further object of the invention is to provide, in a manner as hereinafter set forth, a fan of the four blade type and with the blades so constructed and set to cause the air to pass between the blades at high velocity and practically noiseless.

Further objects of the invention are to provide, in a manner as hereinafter set forth, a fan which is simple in its construction and arrangement, strong, durable, compact, thoroughly efficient in its use, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is a front elevation of a fan in accordance with this invention, and showing the fan connected to the driving means therefor.

Figure 2 is a top plan view of the fan and the driving means therefor.

Figure 3 is a rear elevation of the fan.

Figure 4 is a section on line 4—4 Figure 1.

Figure 5 is a section on line 5—5 Figure 1.

Figure 6 is a section on line 6—6 Figure 1.

Referring to the drawings in detail 1 denotes a base upon which is secured a motor 2 for driving the fan and the latter is secured to the motor shaft 3.

As illustrated the fan comprises a hub 4 having formed integral therewith a set of blades, four in number and indicated at 5, 6, 7 and 8. The hub 4 is formed with an opening 9 having a threaded wall with which engages a suitable holdfast device for securing the hub 4 to the shaft 3. Preferably the fan is cast solid from aluminum to make the operation thereof all the more noiseless.

The blades at their points of joiner with the periphery of the hub 4 are equally spaced with respect to each other. Each blade is formed with a straight leading edge, a convexed outer end edge and a convexed follower edge.

Each blade is diagonally disposed with respect to the hub, and the blade at its inner end is set at 36°, at its center at 24° and at its tip 18°, angle, so that pressure is built up and the air propelled in practically straight lines parallel with the shaft. Each blade gradually decreases in thickness from its outer towards its inner end. The follower edge of the blade, at the inner end thereof, projects beyond the outer peripheral face of the hub. The blade increases in width from its inner end to a point removed from its outer end and then decreases in width from said point to its outer end. The widest part of the blade is positioned forwardly with respect to the transverse median of the blade. The blade is concavo-convex in transverse section from a point in proximity to its inner end to the tip or outer end thereof. The follower portion of the blade overhangs the leading portion thereof which is provided for by setting up the blade of torsional curvature. The curvature of the blades, together with the particular angles which each blade is set as before stated, causes the air to pass through the blades at a high velocity and practically noiseless.

The fan will move large volumes of air at low pressure, and it is especially adapted for heating and ventilating work, then furthermore the construction and arrangement of the blades relative to the hub will propel the air in practically a straight line and therefore it is thought the many advantages of a fan, in accordance with this invention, can

be readily understood, and although the preferred embodiment of the invention is as illustrated and described, yet it is to be understood that changes in the details of construction can be had which will fall within the scope of the invention as claimed.

5 What I claim is:

An air moving fan for warm air furnace work comprising a hub having extending therefrom four equally spaced blades, each 10 of said blades having its body diagonally disposed throughout with respect to the hub and with the angle of inclination of said body gradually decreasing from the inner to the outer end thereof, said body having its inner 15 face for a portion of its length concave and the remaining portion flat, said concave portion being of greater length than said flat portion and positioned outwardly with respect to the latter, said body having its leading edge straight throughout, its outer edge convex throughout and its follower edge convex throughout, the inner portion of said leading edge being positioned outwardly with 20 respect to the inner portion of the follower 25 edge of an adjacent body, said follower edge terminating in said hub and said leading edge having its inner portion spaced from the hub.

30 In testimony whereof, I affix my signature hereto.

GEORGE O. BISHOP.
